Des. 1679

Henry S. and Alfred S. Hubbell of Buffalo, N.Y.
Letter Patent No 1679 Dated Decr 9. 1862.

The schedule referred to in these Letters Patent and making part of the same.

To all whom it may concern:

Be it known that we Henry S. Hubbell and Alfred S. Hubbell of the City of Buffalo, County of Erie and State of New York have invented or produced a new and original design for

Dec. 1679

Cooking Stoves Called the Wild Fire, and we do hereby declare that the following is a full and exact description of the same reference being had to the accompanying Photograph, and the letters of reference made thereon.

Letter A the Top Plate, B. B. B. B the side and side doors, the other side and side doors being like these. C.C. the upper. Front of, stove. D the lower Front of, stove E. E. the front doors F the middle Bottom or Hearth of Stove.

What we claim as our Invention or production, and desire to secure by Letters Patent is the general design and configuration represented in the accompanying Photograph.
